UNITED STATES PATENT OFFICE.

SAMUEL L. HAINES, OF PHILADELPHIA, PENNSYLVANIA.

DESIGN FOR A CORNER-BRACKET FOR BEDSTEADS.

SPECIFICATION forming part of Design No. 32,168, dated January 30, 1900.

Application filed January 6, 1900. Serial No. 627. Term of patent 7 years.

To all whom it may concern.

Be it known that I, SAMUEL L. HAINES, a citizen of the United States, and a resident of the city of Philadelphia, State of Pennsylvania, have invented and produced a new and original Design for a Corner-Bracket for Bedsteads, of which the following is a specification, reference being had to the accompanying drawing, forming part of the invention.

This invention relates to a design for a corner-bracket for bedsteads, adapted for use in securing the corner-posts and side rails of a bedstead together.

15 In the accompanying drawing my new design is illustrated in perspective.

The leading feature of my design consists of a tubular sleeve A, having projecting from one side thereof, adjacent its upper end, the 20 two ears a a, disposed at substantially right angles to the sleeve, the said ears being connected by the pin a', and the two ears b b,

similarly disposed, adjacent the lower end of the said sleeve A and arranged in line with the ears a a, said ears b b being connected by the pin b', as shown in the drawing.

Extending around the sleeve A, about centrally of the projecting ears a a and b b, are the beads or ribs a² and b², respectively, while in the center of the said sleeve is an annular 30 bead or rib c, all arranged substantially as illustrated.

Having thus described my invention, what I claim, and desire to secure by Letters Patent, is—

The design for a corner-bracket for bedsteads, substantially as herein shown and described.

In witness whereof I have hereunto set my hand this 5th day of January, A. D. 1900.

SAMUEL L. HAINES.

In presence of—

BENJ. F. PERKINS,
JNO. T. CROSS.
